BOTTLE CARRIER

William Parks Rocker and Jacob Baum Taylor,
Atlanta, Ga., assignors to Southern Spring Bed
Company, Atlanta, Ga., a corporation of
Georgia

Application April 16, 1941, Serial No. 388,884

1 Claim. (Cl. 224—48)

This invention relates to display carrier devices and more particularly to devices of the type commonly employed to display and transport relatively small groups of bottles or other containers.

In accordance with the invention, a display carrier is provided which is so designed and constructed that the bottles grouped together are not only displayed prominently when the carrier is in actual use and are safely held for convenient handling, but may also be collapsed so as to occupy but small space when the carrier is not in use. It has been customary heretofore to provide dispensers of bottled goods, particularly beverages, with paper-board carriers for small groups of bottles, each such carrier comprising a well or receptacle for the bottles, generally six, and an upstanding carrying or suspending means which may be readily grasped in the hand, the carrier being usually given away when a consumer purchases all of the bottles which it contains.

The carrier which comprises the subject-matter of the present invention, however, is of durable type, capable of being used many times, is collapsible so that it may be readily stored in small space when not in use, is attractive in appearance and may be constructed at small cost. It likewise is so constructed that wear and tear on the bottles which it may contain while being handled is minimized, the carrier contracting around the bottles when loaded and in use, pressing the bottles against each other and thus avoiding rattling and chipping of the glass. Likewise, the improved carrier has the advantage of including a carrying bail or handle which may be vertically displaced when the carrier is not being moved about, the bail being lowered below the tops of the bottles which the carrier contains, thus making it possible for the bottom of one carrier to be placed directly upon the tops of the bottles of the carrier below. In other words, the type of carrier contemplated by the invention permits stacking of carriers one upon the other, a feature of considerable advantage under many circumstances.

The design and arrangement of the various component elements of the improved carrier may be considerably varied in adapting the same for the reception, storage and transportation of bottles of different sizes and characteristics, as will be appreciated by one skilled in the art, and that embodiment which is illustrated in the accompanying drawings and will be hereinafter described in detail, has been selected for disclosure by way of example only.

In the drawings:

Figure 1 is a perspective view of the carrier, a group of six bottles which it holds being indicated in chain lines;

5 Figure 2 is a perspective view of the carrier in a partially collapsed and empty condition;

Figure 3 shows the carrier in fully collapsed condition;

10 Figure 4 is a side elevation of the carrier of the preceding views but showing, attached to the side thereof, a display surface for advertising matter; and

15 Figure 5 is an end elevation of the carrier showing the carrying or suspending means in operative position in dotted lines and in folded position in full lines.

20 As clearly shown in the drawings, the carrier is fabricated of rod-like members of small diameter and these rod-like members may conveniently be sections of metal wire wrought into the shapes shown, wire being easily worked into desired shape, readily welded, sufficiently stiff so as to maintain its shape and yet, when formed of metal of the desired composition and having the 25 desired diameter, possessing a considerable resiliency which is advantageous when the carrier is in use.

25 The carrier bottom is grid-like, comprising a plurality of parallel bottom elements 19, the ends of which rest upon and are secured to, preferably by welding, the parallel transversely disposed end elements 11. Each carrier side includes a main member which is U-shaped, having a bottom bar 12 and upwardly extending parallel legs 13, together with a top bar 14 and an intermediate bar 15, the top and intermediate bars being parallel to the bottom bar 12 and welded to the 30 upstanding legs 13. The bottom bar 12 of each side is pivotally attached to the carrier bottom, the ends 11' of bars 11 being loosely looped around bar 12, as shown. The ends of the intermediate side bars 15 are provided with loops 15' and linking the loops 15' together are the end bars 17, each bar 17 having looped ends 17' which 35 engage with the looped ends 15' of the intermediate bars 15 of the sides. It will be perceived that the end bars 17 function to maintain the carrier sides in parallel relationship and these bars also function, when the carrier is loaded, to prevent escape of bottles.

40 Connected to the tops of the two carrier sides is the carrying or suspending means and this carrying or suspending means comprises the bail member 20 which preferably has the form of an 45 inverted U and is provided with triangular loops 50 55

20' at its ends, and four link members 21, each such member having a looped end 21' which passes through a similarly formed loop 14' at the end of the top member 14 of the adjacent side, and a loop 21² through which loosely encircles the bottom bar of the triangular loop 20' of the bail 20. With the various parts of the carrier disposed in the positions in which they are illustrated in Figure 1, six bottles may be readily inserted and these bottles occupy practically all of the carrying space available, as indicated in Figure 5. The bottles when full have a very considerable weight and, when the carrier and its contents are suspended by means of the bail 20, the sides will be flexed inwardly due to the inward pull exerted by each link 21 upon the upper end of the associated side member 13, bringing the top side bars 14 into contact with the sides of the bottles, thus moving the bottles toward each other and into contact so that, so long as the carrier and its contents continue to be suspended, the bottles will be largely held against rattling, at least the possible movement of one bottle relative to another is greatly curtailed. The legs 13 of the side members are of such composition, diameter and length as to permit the necessary flexures to occur.

When emptied of its contents, the carrier may be readily re-charged or may be collapsed and, in Figure 2, it is shown in a partially collapsed condition, the bail 20 being down-turned and the sides having been partially tilted with respect to the base. In Figure 3, the various elements of the carrier are shown in the positions which they occupy when the carrier is completely collapsed and it will be seen that the carrier occupies but small space and may be readily handled and stored.

In Figure 5, the carrier is shown in end view, with contents in chain lines, the suspending means being illustrated in dotted lines in the position which it occupies when the carrier is being transported, and being shown in full lines in downwardly deflected position, the bail 20 and links 21 being below the plane which includes the tops of the bottles. With the bail so positioned, the bottom of a second carrier may be placed directly upon the tops of the bottles contained in the carrier shown, two carriers being thus stacked one upon the other. If desired, a further carrier may be placed upon the second, etc., so that a considerable number of carriers may be stacked.

In Figure 4, the carrier previously described is shown to have affixed to its side a display card or plate indicated at 25, this plate being preferably a light metal sheet, the upper edge of which is rolled over the top bar 14 of the side and the lower edge of which is rolled over or around the intermediate bar 15 of the side. Upon this display guard or sheet may be inscribed any suitable legends advertising the beverages contained in the bottles which the carrier is primarily intended to receive. Naturally, the carrier will

serve its purpose best when dimensioned so as to receive a definite number of bottles of definite diameters and heights, but, of course, it will be of considerable utility when employed for the storage and transportation of bottles of other sizes and characteristics and, indeed, in handling articles other than bottles. In Figure 5, the leg members 13 of the sides of the carrier are shown to be substantially curved or inwardly deflected. It will be appreciated that this inward flexure need only be very slight in the average case, to be of advantage when the bottles have the diameters for which the carrier is preferably designed.

Having thus described the invention, what is claimed as new and desired to be secured by Letters Patent is:

A collapsible bottle carrier comprising a bottom member, substantially rectangular side members each hingedly connected to the bottom member for swinging movement in either direction of rotation about parallel axes lying in the plane of the bottom member and to a limit of movement wherein either one of said side members lies substantially in said plane and the other is disposed in a substantially parallel plane against the bottom member when the carrier is collapsed, a link pivotally connecting corresponding ends of said side members at each end of the carrier, said links being attached to said side members above the bottom member and well below the upper edges of the rectangular side members and being disposed parallel to the end edges of said bottom frame, said links being of a material sufficiently rigid to maintain the lower portions of the side members in parallelism at all times, resisting departure from such parallelism whether arising from movement of said side members toward or away from each other, and carrying means comprising an inverted U-shaped bail member and a pair of links at each end of said bail member, the links of each pair extending in opposite directions toward the side members, each link having one of its ends pivotally connected with the bail member and its opposite end pivotally connected to the upper portion of the adjacent side member, each of the links being of a length substantially equal to one-half the distance from one side member to the other when in position for use, and the height of the bail member being at least equal to the length of one of said links, at least the upper portions of said side members being resilient so that their upper edges will be drawn inwardly toward each other when the loaded carrier is supported by the bail member, the lower portions still being maintained in parallelism by means of said links and the bottom connections and further so that the bail member may be displaced downwardly and outwardly to completely uncover the articles disposed within the carrier to permit stacking or ready removal of said articles in any sequence desired.
